UNITED STATES PATENT OFFICE.

BILLY S. McCAIN, OF KNOX COUNTY, INDIANA.

PUZZLE.

No. 821,182.

Specification of Letters Patent.

Patented May 22, 1906.

Application filed June 14, 1905. Serial No. 265,254.

To all whom it may concern:

Be it known that I, BILLY S. McCAIN, a citizen of the United States, residing in the county of Knox and State of Indiana, have 5 invented certain new and useful Improvements in Puzzles, of which the following is a specification.

This invention relates to an improved puzzle of that type wherein a board is tilted from side to side in an attempt to get a number of balls into a certain pen or inclosure.

It is intended to call the puzzle "Pigs in the corn-field," and it consists, essentially, of a board subdivided by partitions, which represent 15 rows of corn, into a series of compartments, said compartments having communication with each other through openings in the partitions and also through passages beneath the surface of the base. In order to 20 solve the puzzle, it is necessary to so manipulate it as to get all the pigs, which are represented by small balls, into a pen.

It has for its object to produce a device of this character which will be simple and durable 25 in construction, which will be very attractive and interesting, and which can be manufactured at a comparatively small cost.

For a full description of the invention and the merits thereof and also to acquire a 30 knowledge of the details of construction of the means for effecting the result reference is to be had to the following description and accompanying drawings, in which—

Figure 1 is a top plan view of the puzzle. 35 Fig. 2 is a bottom plan view with the lower section of the base removed and showing the construction of the internal passages. Fig. 3 is a sectional view on the line X X of Fig. 1.

Corresponding and like parts are referred 40 to in the following description and indicated in all the views of the drawings by the same reference characters.

The numeral 1 designates the base, which is surrounded by perpendicular walls 2. A 45 series of approximately parallel partitions 3 divide the board into a number of compartments which have communication with each other through openings 4 in the lower portion of said partitions. The pen 5 is formed at 50 one side of the board by cutting away a portion of one of the partitions 3 and employing transverse members 6. For convenience of manufacture the base is preferably made in three sections. The upper section 7 is provided 55 with a series of openings 8, which lead into passages formed by slots in the middle

section 9 and are bored at an angle to the surface of the board, so as to form an inclined plane and enable the balls to readily pass through them. The middle section 9 is 60 formed with a main slot 10, having a number of arms 11, which have communication with the openings 8 in the upper section. The lower section simply fits over the slots in the middle section, so as to form a closure for the 65 passages which have external communication through the openings 8.

A number of balls 13 are used in connection with the above-described device, and when the board is tilted from side to side the 70 balls pass from one compartment to the other through the openings in the partitions or through the passages in the base. Owing to the peculiar arrangement of the passages, it will be readily understood that the balls 75 first pass to the central passage and from thence may come to the surface at any point on the board. It is therefore very largely a matter of chance and patience to get all the balls within the pen.

Having thus described the invention, what is claimed as new is—

1. In a puzzle, the combination of a base provided with a system of internal passages having communication with the surface 85 thereof, a series of walls forming compartments having communication with each other through the internal passages, and balls adapted to roll through the passages.

2. In a puzzle the combination of a base 90 provided with a system of internal passages comprising a central passage having arms extending therefrom and having communication with the surface, walls forming a series of compartments having communication 95 with each other through the internal passages, and balls adapted to roll through the passages.

3. In a puzzle, the combination of a base provided with a system of internal passages, 100 comprising a central longitudinal passage and transversely-extending arms in communication therewith, walls subdividing the base into a number of compartments having communication with each other through the 105 internal passages, and balls adapted to roll through the passages.

4. In a puzzle, the combination of a base formed with a system of internal passages comprising a central passage and arms extending 110 therefrom, walls forming a series of compartments having communication with

each other through the internal passages and through openings in the walls, and balls adapted to pass through the openings in the walls and the passages in the base.

- 5 5. In a puzzle, the combination of a base formed in sections, the middle one being provided with a number of slots, the upper one having openings in communication with said slots while the lower one forms a closure,
- 10 walls forming a series of compartments having communication with each other through the internal passages in the base formed by the slots in the middle section thereof, and balls adapted to roll through the passages.
- 15 6. In a puzzle, the combination of a base formed with a system of internal passages having communication with the surface, a wall around the base, a series of parallel partitions forming compartments having communication with each other through the internal passages, a pen into which it is the ob-
- 20

ject to get the balls, and balls adapted to roll through the passages in the base.

7. In a puzzle the combination of a base provided with a series of internal passages having communication with the surface thereof, a wall around said base, a series of approximately parallel partitions having openings therein and subdividing the base into a number of compartments, a pen formed by cutting away a portion of one of the parallel partitions and employing two transverse partitions one of them having an opening therein, and a number of balls adapted to pass through the openings in the partitions and the internal passages in the base.

In testimony whereof I affix my signature in presence of two witnesses.

BILLY S. McCAIN. [L. s.]
